L. S. SNELL

TRACK SIGNAL

Filed June 14, 1921

Inventor
L. S. Snell.

By Attorney

UNITED STATES PATENT OFFICE.

LEROY S. SNELL, OF UTICA, NEW YORK.

TRACK SIGNAL.

Application filed June 14, 1921. Serial No. 477,435.

To all whom it may concern:

Be it known that I, LEROY S. SNELL, a citizen of the United States, residing at Utica, in the county of Oneida and State 5 of New York, have invented certain new and useful Improvements in a Track Signal; and I do hereby declare the following to be a full, clear, and exact description of the invention, such as will enable others skilled 10 in the art to which it appertains to make and use the same.

The invention relates to signals designed for use on railways to warn the engineer or other train operator of impending danger 15 when the usual signal is not heeded because of fog or other cause.

Other objects and advantages will be apparent and suggest themselves as the nature of the invention is understood.

20 While the drawing illustrates an embodiment of the invention it is to be understood that in adapting the same to meet different conditions and requirements, various changes in the form, proportion and minor 25 details of construction may be resorted to without departing from the nature of the invention.

Figure 1 is a side view of the mechanical operating parts of my invention, the casing 30 or housing therefor being shown in section,

Figure 2 is a view showing the electric circuit employed, the mechanical parts of the device being diagrammatically shown.

The operating parts of the mechanism are 35 enclosed for protection against the elements and to prevent tampering therewith. The casing or box for receiving the working parts is designated by the numeral 1 and is provided in a side with an opening 2 through 40 which a bar 3 is adapted to pass when it is required to place a torpedo 4 upon a rail 5 of the track. The bar 3 has a portion toothed as indicated at 6 to mesh with the teeth of the gear wheel 7. Posts or guides 8 45 and 9 slidably support the bar 3. The gear wheel 7 is fast to a shaft 10 journaled to the uprights 11 or like supporting means. A pulley 12 secured to the shaft 10 is belted or otherwise connected to a motor 13 where- 50 by the shaft 10 may be positively rotated forwardly or backwardly to advance or withdraw the bar 3. In the preferable construction, the motor 13 is of the electric type and of such construction as to be reversed.

55 A belt 14 connects the pulley 12 with a com-

panion pulley 15 secured to the armature or shaft of the motor 13. The motor 13 is included in an electric circuit which is adapted to be controlled from a determinate point. Two push buttons 16 and 17 are provided 60 at the point of control. When the circuit through the motor 13 is closed by pressing the button 16 the motor is operated to advance the bar 3 whereby the torpedo 4 is placed upon the rail 5. When the circuit is closed by pressing the button 17 the motor 13 is reversed thereby withdrawing the bar 3 and the torpedo carried thereby provided the same has not been exploded. Lamps 18 and 19 are included in the circuit, the lamp 18 being red and indicating danger and the lamp 19 green to designate caution.

The bar 3 is provided with a pin or stop 22 which is adapted to cooperate with contacts 20 and 21 applied to the respective 75 posts 8 and 9.

As herein before stated, the motor 13 is reversible. The letter B represents a battery or source of electric supply. A wire 23 connects the plus pole of the battery with 80 one terminal of the motor 13 and a wire 25 connects the other terminal of the motor 13 with the switch 16. Wires 31 and 26 connect contacts of the two switches 16 and 17 with the minus pole of the battery B. 85 When the switch 16 is closed, the circuit through the motor for advancing the rod 3 is as follows: From the positive pole of the battery B through wire 23, motor 13, wire 25, switch 16 and wires 31 and 26 to the minus pole of the battery B. When the bar 3 reaches a position to place the torpedo 4 upon a rail 5 of the track, the lighting circuit to the lamp 18 is as follows: From the positive pole of battery B through wires 90 23, 27 and 28, switch 22—21, wire 29, lamp 18 and wires 31 and 26 to the minus pole of the battery B. When the switch 17 is closed to reverse the motor 13 and return the bar 3 to normal position, the circuit is as fol- 95 lows: from the positive pole of battery B through wire 23, motor 13, wire 30, switch 17 and wires 31 and 26 to the minus pole of the battery B. When the bar 3 reaches its normal position, the circuit including the 100 lamp 19 is closed by the switch 22 and 20, the circuit starting from the plus pole of the battery B being as follows: Wires 23, 27 and 28, switch 22—20, wire 32, lamp 19 and wires 31 and 26 to minus pole of battery B. 105 110

Having thus described the invention, what I claim is:—

1. A track signalling mechanism including a torpedo-carrying bar, uprights on which said bar is slideable, a pin extending laterally from the bar and disposed intermediate said uprights, said pin adapted to engage the uprights to limit movement of the bar in opposite directions, signals in electric circuits having spaced contacts on said bars and adapted to be engaged by said pin to close said circuits.

2. A track signalling mechanism including a casing, uprights within the casing and in spaced relation, a torpedo carrying bar slidably mounted by said uprights, said bar being normally disposed within the casing, the casing having an opening through which the bar may slide, said bar having

gear teeth, a gear wheel in mesh with said teeth, means within the casing journaling said gear wheel, a reversible motor operable to slide said torpedo carrying bars in opposite directions and located within the casing, a pin extending laterally from the bar and disposed intermediate said uprights, said pin adapted to engage the uprights to limit movement of the bar in opposite directions, signals in electric circuits having spaced contacts disposed on said bars and adapted to be engaged by said pin to close said circuits.

In testimony whereof I affix my signature in presence of two witnesses.

LERoy S. SNELL.
